(57) **CLAIM**

The ornamental design for an extendable outlet, as shown and described.

DESCRIPTION

FIG. 1 is a front perspective view of a moveable outlet shown in a first position;

FIG. 2 is a rear perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof;

FIG. 8 is a right side view thereof;

FIG. 9 is a top view thereof, in an environment of use; and,

FIG. 10 is another top view thereof, shown in a second position, in an environment of use.

The broken lines in the drawings are for the purpose of illustrating environmental subject matter and portions of the extendable outlet that form no part of the claimed design.

1 Claim, 8 Drawing Sheets
